UNITED STATES PATENT OFFICE.

ELI EPSTEIN, OF BOSTON, MASSACHUSETTS.

CYLINDER-LOCK.

1,257,987.

Specification of Letters Patent.

Patented Mar. 5, 1918.

Application filed December 15, 1917. Serial No. 207,226.

To all whom it may concern:

Be it known that I, ELI EPSTEIN, a citizen of the Republic of Russia, residing at Boston, county of Suffolk, State of Massachusetts, have invented an Improvement in Cylinder-Locks, of which the following description, in connection with the accompanying drawing, is a specification, like characters on the drawing representing like parts.

In United States Patent No. 1,244,304, issued to me October 23, 1917, I have illustrated and described a cylinder lock which has the usual spring-pressed tumbler pins carried by the casing, and in addition thereto, a tubular spring-pressed tumbler element carried by the plug and encircling one of the drivers and adapted to have interlocking engagement with the casing, said tubular tumbler element being constructed so that it is withdrawn from interlocking engagement with the casing by the insertion of the key which lines up the tumbler pins.

My present invention relates to a cylinder lock of this type and has for its object to improve such a cylinder lock in the various features hereinafter pointed out.

In order to give an understanding of my invention, I have illustrated in the drawings a selected embodiment thereof which will now be described, after which the novel features will be pointed out in the appended claims.

Figure 1 is a vertical sectional view through a cylinder lock embodying my invention;

Fig. 2 is a section through the casing on the line 2—2, Fig. 4, with the plug, drivers and tumbler pins removed;

Fig. 3 is a view of the plug;

Fig. 4 is a section on the line 4—4, Fig. 1;

Fig. 5 is a section on the line 5—5, Fig. 1;

Fig. 6 is a section similar to Fig. 4 showing the key inserted and the tumbler elements lined up;

Fig. 7 is a perspective view of the tumbler element carried by the plug;

Fig. 8 is a view of the key which is used;

Fig. 9 is a fragmentary sectional view similar to Fig. 1 showing the tumblers lined up by the key.

My improved lock comprises the usual casing 1 which may have any suitable construction and which is provided with sockets or spaces 2 for the reception of the usual

tumbler pins 3, each tumbler pin being backed by a suitable spring 4, and it also comprises the usual plug 5 which is rotatably mounted in the casing and is formed with the key-way 6, said plug carrying the drivers 7 which are acted on by the key and which serve to line up the tumbler pins 3. The parts above referred to may have any suitable or usual construction. The tumbler elements 3 which are carried by the casing normally have interlocking engagement with the plug, and in addition to such tumbler elements, the device herein illustrated has a tubular tumbler element 8 which is carried by the plug 5 and which normally has interlocking engagement with the casing, as shown in my above-mentioned patent.

One feature of my present invention relates to the shape and construction of this tubular element 8 by which the manufacture of the lock may be cheapened and simplified. The tumbler element 8 is made from a section of tube, and it encircles one of the driver elements, the aperture 9 in the plug in which said driver element operates being of the proper size to receive the tumbler element 8.

The tube section from which the tumbler element 8 is made is cut away at one end, as at 10, to form a key-receiving space thereby producing the two depending portions 11 and 12 situated on opposite sides of the tubular element. The portion 12 is longer than the portion 11 and the lower end thereof is bent laterally to provide a foot 13 that projects into the keyway. The tumbler element 8 is also provided with a laterally-extending projection 14 which operates in a recess 15 formed in the plug, said recess receiving a spring 16 which acts against the projection 14 and tends to urge the tumbler element 8 outwardly into interlocking engagement with the casing.

The casing is provided with a recess 17 opposite the aperture 9 into which the end of the tumbler element 8 is projected by the spring 16 when the lock is locked.

The key for operating the lock is indicated at 18 and it is shown as provided with a groove 19 in one side which fits the ledge or rib 20 formed in one side of the keyway. When the key is inserted, the upper wall 21 of the groove 19 will engage the lip 13 and draw the tubular element 8 downwardly out of engagement with the casing and at the

same time, of course, the serrated edge 22 of the key will act on the drivers to line up the tumbler elements 3, thus unlocking the plug.

The extension 11 acts as a guide to assist 5 in preventing any tendency of the tumbler element 8 to tip or bind in the aperture 9. Further, the tumbler element shown herein can be quickly and cheaply made from a section of tubing.

10 In order to increase the security of the lock, I have made the upper end of the tumbler element 8 with one or more projections 23 which are arranged so that they extend slightly beyond the periphery of the plug when the 15 tumbler element 8 is retracted by the key, as shown in Fig. 9. The casing is provided with a groove 24 in line with each projection 23, said grooves 24 having a gradually-decreasing depth from their central position around to about the point 25 in Fig. 5. When the key 18 is inserted and the tumbler elements are lined up, the main portion of the tumbler element 8 will be withdrawn 20 from interlocking engagement with the casing, and the projections 23 will be withdrawn from the recess 17 into the grooves 24. The plug may then be turned as usual by means of the key thereby releasing the lock.

The presence of the projections 23 makes 30 it impossible to insert any lock-picking implement between the plug and casing even when the tumbler element 8 is properly lined up because these projections 23 extend into the grooves 24. Since the grooves 24 are of 35 gradually-decreasing depth and terminate at the point 25, the turning of the plug through an angle of 90° from its central position will carry the projections 23 out of the grooves thereby permitting the plug to be removed 40 if such action is desired.

In order to make the lock still more secure, I have so constructed one of the drivers 7 that is situated at the front of the tumbler element 8 so that it has a length longer than 45 the distance from the periphery of the plug to the rib 20. In the drawings the driver nearest the front of the plug is the long driver, said driver being indicated at 70. This use of this long driver 70 will necessarily 50 form the key 18 with a correspondingly deep recess 26 so that when the key is inserted, the driver 70 will be properly lined up. Since the driver 70 extends below the shoulder 20, the bottom of the recess 26 will 55 have to extend below the edge 21 of the groove 19. The reason for this construction is that if the driver element 70 were short like the other drivers so that the lower end thereof was above the rib 20, it would be 60 possible to take a key similar to the key 19 and to cut off the serrated edge 22 and then by inserting said key to withdraw the tumbler element 8. Then while the key was held in the lock, the lock might be jarred thereby 65 to line up the other tumbler elements 3 and

release the lock. By making the driver 70 of such length that the lower end thereof projects below the rib 20, it will be observed that if a skeleton key with simply the groove 19 and shoulder 20 is inserted thereby to line up the tumbler element 8, the engagement of said key with the longer driver 70 will force it into interlocking engagement with the casing and hold it there thereby locking the plug so that the lock could not be released even if it were jarred so as to line up the other tumbler elements. My improved lock is, therefore, doubly secure.

I claim:

1. In a cylinder lock, the combination 80 with a casing, of a plug rotatably mounted therein and provided with a keyway, spring-pressed tumbler pins carried by the casing and adapted to have interlocking engagement with the plug, drivers carried by the 85 plug and by which the tumbler pins are lined up by the insertion of a key in the keyway, and a tubular spring-pressed tumbler element carried by the plug and encircling one of the drivers and adapted to have interlocking engagement with the casing, said tubular tumbler element being cut away at one end to form a key-receiving opening and presenting two depending guiding portions either side of said opening, one 95 of said guiding portions having a key-engaging lip projecting from its lower end.

2. In a cylinder lock, the combination 100 with a casing, of a plug rotatably mounted therein and provided with a keyway, spring-pressed tumbler pins carried by the casing and adapted to have interlocking engagement with the plug, drivers carried by the 105 plug and by which the tumbler pins are lined up by the insertion of a key in the keyway, and a tubular spring-pressed tumbler element carried by the plug and encircling one of the drivers and adapted to have interlocking engagement with the casing, said tubular tumbler element being cut away at 110 one end to form a key-receiving opening and presenting two depending guiding portions either side of said opening, one of said guiding portions having a key-engaging lip projecting from its lower end, said tubular 115 tumbler element having a lateral projection, and a spring carried by the plug exterior to said tubular element and acting against said projection.

3. In a cylinder lock, the combination 120 with a casing, of a plug rotatably mounted therein, spring-pressed tumbler elements carried by the casing and normally held in interlocking engagement with the plug, a spring-pressed tumbler element carried by the plug 125 for movement in a direction parallel to the direction of movement of the first-named tumbler elements and adapted to have interlocking engagement with the casing, and means associated with all the tumbler ele- 130

ments whereby they are lined up by the insertion of the key in the keyway of the plug, the tumbler element carried by the plug having a projection which extends beyond the periphery of the plug when said tumbler element is lined up and the casing having a groove to receive said projection and permit turning movement of the plug.

4. In a cylinder lock, the combination with a casing, of a plug rotatably mounted therein and provided with a keyway, tumbler pins carried by the casing and adapted to have interlocking engagement with the plug, key-actuated drivers carried by the plug for lining up the tumbler pins, a tubular spring-pressed tumbler element carried by the plug and encircling one of the drivers and normally having interlocking engagement with the casing, and means to line up said tubular element upon the insertion of a key, said tubular element having a projection at its end which extends beyond the periphery of the plug when said element is lined up and the casing having a groove to receive said projection as the plug is turned.
5. In a cylinder lock, the combination with a casing, of a plurality of spring-pressed tumbler pins carried thereby, a plug rotat-

able in said casing, key-actuated drivers carried by the plug, a tumbler element carried by the plug and normally having interlocking engagement with the casing, said tumbler element having a depending portion with a laterally-extending foot to be engaged by the key, one of the driver pins having a length to extend below said foot.

6. In a cylinder lock, the combination with a casing, of a plurality of spring-pressed tumbler pins carried thereby, a plug rotatably mounted in the casing and provided with a keyway presenting a rib at one side, key-actuated drivers carried by said plug, a spring-pressed tumbler element carried by the plug and normally having interlocking engagement with the casing, said tumbler element having a foot in line with said rib whereby when the key is inserted the wall of the groove in the key which embraces the rib will engage the foot and withdraw the tumbler element from engagement with the casing, one of the drivers being of a length so that its lower end extends below said rib.

In testimony whereof, I have signed my name to this specification.

ELI EPSTEIN.
